R. W. BURNETT.
ROOF.
APPLICATION FILED OCT. 18, 1911.
1,083,239. Patented Dec. 30, 1913.

UNITED STATES PATENT OFFICE.

RICHARD WEBB BURNETT, OF MONTREAL, QUEBEC, CANADA.

ROOF.

1,083,239.

Specification of Letters Patent. Patented Dec. 30, 1913.

Application filed October 18, 1911. Serial No. 655,366.

To all whom it may concern:

Be it known that I, RICHARD WEBB BURNETT, residing at the city of Montreal, Province of Quebec, Dominion of Canada, have 5 invented certain new and useful Improvements in Roofs; and I do hereby declare that the following is a full, clear, and exact description thereof.

My invention relates particularly to car 10 roofs and it has for its object to provide a self-sustaining water-tight roof suitable for all types of cars.

The invention may be said to consist of 15 roof plates combined with external carlines and means for connecting the plates to the carlines in a manner to dispense with the usual ridge-pole, purlins, sheathing and other roof carrying parts. For full comprehension, however, of my invention reference must be had to the accompanying drawings forming a part of this specification in 20 which similar reference characters indicate the same parts, and wherein:

Figure 1 is a plan view of a portion of a 25 car roof constructed according to my invention; Fig. 2 is a side elevation thereof; Fig. 3 is a longitudinal vertical sectional view taken on line A-A Fig. 1; Fig. 4 is a similar view to Fig. 3, the view being taken on line 30 B-B Fig. 1; Fig. 5 is a transverse vertical sectional view taken on line C-C Fig. 1; and Fig. 6 is an enlarged detail transverse vertical sectional view of the side edge of the roof.

In the preferred embodiment of my invention the roof plates consist of flanged 35 corrugated sheets 2; the carlines extend from side to side of the car roof and consist of relatively heavier steel plates 3 bent to inverted U-form with flanged edges 4; and the means for fastening the roof-plates to these carlines consist of a series of sheet steel clips 5 riveted at one end to the under side 40 of the flanges of the carlines and bent back upon themselves to inclose and support the flanged edges, indicated at 10, of the roof-plates. This arrangement places the carlines above the roof-plates.

The roof is preferably arched and connected to the Z-bars 20 forming the top 50 plates of the side framing of the car by bending down the ends of the carlines proper and roof-plates and riveting or otherwise fastening them to such Z-bars.

The manner of assembling the members of 55 my improved roof is as follows: The outer

legs of the clips 5, relatively to the carline, are first bent and riveted to the flanges of the carline, the inner legs remaining straight. The flanged edges of the roof 60 plates are inserted into the clips, the inner legs of which are bent over, thus completing the roof. Owing to the particular construction of the carlines in conjunction with the flanges and corrugations of the roof- 65 plates, the roof thus formed has flexibility and strength while allowing comparatively light-weight roof sheets to be used. The flanges of the carlines are recessed as at 22 to accommodate the clips and bring their 70 under surfaces flush with the under surfaces of the flanges.

I fasten the running boards 25 in place by brackets 26 of channel form and spaced a distance apart equal to the width of the 75 running board, a saddle for the boards being presented by a strip 27 of angle-iron cut away at its ends to fit over the brackets to which it is riveted; and a strap 29 covering the abutting ends of the boards has 80 its ends 30 bent down over the brackets and beneath the same where they are riveted. These running boards 25 preferably consist of shallow steel channels having their tread surfaces roughened to provide a secure foot-hold, and their ends are supported by brackets 31 fixed upon the ends of the car.

Among other advantages besides lightness of construction, the roof-plates are sustained entirely by the exterior carlines and 90 are not punctured at any point, the result is that complete clearance is obtained beneath the roof, and leakage is prevented.

If desired the running board may be made of sufficiently heavy material to enable the 95 angle-iron strip and retaining strap to be dispensed with, the board being in that case riveted directly to the brackets, without departing from the spirit of my invention.

What I claim is as follows:—

1. The combination with a car body, of a metal roof comprising flanged carlines of inverted U-form, roof sheets having flanged side edges, a device for supporting the flanged edges of the roof sheets within the 10 carlines, comprising a part secured to one leg of the U-form carline, and a part supported by said secured part and supporting an edge of the roof sheet.

2. The combination with a car body, of a 11 metal roof comprising sheet metal carlines of inverted U-form with flanged edges, roof

sheets with upwardly flanged edges enveloped by the carlines, and angular clips secured to the flanged edges of the carlines and suspending the said flanged edges of the roof sheets from the carlines.

3. The combination with a car body, of a metal roof comprising carlines of inverted U-form with flanged edges, roof sheets with upwardly flanged edges enveloped by the carlines, and means for suspending the flanged edges of the roof sheets from the carlines, comprising a return bent angular member having one portion secured to the flanged edge of the carline, the other end of said securing member extending beneath a portion of the roof sheet.

4. The combination with a car body, of a metal roof comprising carlines of inverted U-form with flanged edges, roof sheets with upwardly flanged edges enveloped by the carlines, and means for suspending said roof sheets from the carlines, comprising a member secured to the flanged edges of the carlines, said member having a U-shaped por-

tion extending within the channel of the carline and enveloping the upwardly-extending flange of the roof sheet, and a laterally-extending portion extending beneath the flanged edge of the roof sheet.

5. The combination with a car body, of a metal roof comprising carlines of inverted U-form with flanged edges, roof sheets with upwardly flanged edges enveloped by the carlines, and means for suspending the roof sheets from the carlines, secured to the flanged edges thereof above the plane of the main portion of the roof sheet, said securing means having a supporting portion extending below the plane of the roof sheets.

In testimony whereof I have signed my name to this specification in the presence of two witnesses.

Montreal, October 12, 1911.

RICHARD WEBB BURNETT.
